HYDROGENATION AND COKING OF HEAVY PETROLEUM FRACTIONS

Vern W. Weekman, Jr., Rome, N. Y., assignor to Socony Mobil Oil Company, Inc., a corporation of New York

Application August 17, 1956, Serial No. 604,749

9 Claims. (Cl. 208—50)

The present invention relates to the upgrading of heavy petroleum fractions and, more particularly, to the upgrading of long and short residua.

Heretofore, it has been common practice to upgrade heavy petroleum fractions by vis-breaking and coking. Conventional coking processes for upgrading heavy petroleum fractions, such as residua, require regular periodic shutdowns for the removal of the coke deposits from the coking unit. Conventional petroleum coke is difficult to remove from the unit. Conventional coking operations do not reduce the sulfur content of the liquid products appreciably. In addition, the liquid products produced in the conventional coking operations are usually highly unsaturated. Because of the high sulfur content of the liquid products from conventional coking processes, it is necessary to treat the liquid products to remove the sulfur.

The process of the present invention produces a very finely divided easily removed coke which can be removed continuously from the unit, thus imparting continuity of operation to the process.

Furthermore, 80-90 percent of the sulfur of the charge stock is removed and the liquid products are much less unsaturated than the liquid products produced by conventional coking processes. Finally, the liquid products have a higher A. P. I. gravity than the charge stock, a greater yield of gasoline is obtained and the heavier than gasoline fractions have a higher Diesel index than corresponding liquid products produced by conventional coking processes.

The present invention provides for mildly hydrogenating the charge stock and coking the hydrogenated charge. The basic combination of operations, i. e., mild hydrogenation followed by coking of the hydrogenated charge stock, can be modified in many ways. For example, the heavier than gasoline fraction of the coker effluent can be in part or wholly returned to the coker or to the hydrogenation unit. Similarly, the heavier than gasoline fraction of the coker effluent can be subjected to more severe hydrogenation. These and other advantages and modifications of the basic concept of mildly hydrogenating coker charge stock before coking will become apparent to those skilled in the art from the following description taken in conjunction with the drawings in which

Figure 1 is a highly schematic flow-sheet illustrating mild hydrogenation of a heavy petroleum fraction such as a long or short residuum followed by coking of the hydrogenated charge stock, and

Figure 2 is a highly schematic flow-sheet illustrating mild hydrogenation of a heavy petroleum charge stock followed by coking of the hydrogenated charge stock in which the heavier than gasoline fraction of the coker effluent is subjected to severer hydrogenation.

In accordance with the principles of the present invention a heavy petroleum fraction such as a residuum can be mildly hydrogenated and then coked in accordance with the manipulation illustrated by the flow-sheet in Figure 1. Thus, a heavy petroleum fraction, for example a residuum having the following characterizing attributes:

1	2

flows under reaction pressure from a source not shown through line 1. In the beginning and at other times during operation as is necessary hydrogen or gases containing at least 25 percent hydrogen flow under reaction pressure from a source not shown through line 4 to line 1 under control of valve 5. At other times hydrogen-containing recycle gas, obtained as hereinafter described flows from line 6 through line 7 under control of valve 8 to line 1. The mixture of heavy petroleum fraction and hydrogen-containing gas in the molar ratio of about 1.5 to 25 mols of hydrogen per mol of heavy petroleum fraction or about 300 to 5000 standard cubic feet of hydrogen per barrel of feed (s. c. f./b.) flows through line 1 under reaction pressure to coil 2 of heater 3.

In coil 2 of heater 3 the charge mixture of heavy petroleum fraction and hydrogen-containing gas is heated to a reaction temperature. The heated charge flows from coil 2 through line 9 to line 10. In line 10 the charge mixture containing the fresh charge stock is mixed with hot liquid recycle drawn from line 11 under control of valve 12 by pump 13 through line 14 and discharged through line 15 into line 10.

The mixture of charge mixture and hot liquid recycle flows through line 10 to line 16.

When reaction conditions permit, e. g., when the temperature and quantity of recycle gas mixed with the fresh charge and the hot liquid recycle does not reduce the temperature of the mixed gas and oil below reaction temperature, recycle gas can be mixed with the fresh charge and the hot liquid recycle without heating the recycle gas by closing valve 8 and opening valve 17 in line 18. On the other hand, a portion of the recycle gas can be mixed with the fresh charge and heated therewith and a portion can be introduced through line 18 under control of valve 17.

The reactor feed comprising fresh charge, e. g., residuum, and hot liquid recycle in the ratio of about 0 to 10 volumes of hot liquid recycle per volume of fresh charge and hydrogen containing gas in the ratio of about 0.5 to 25 mols hydrogen per mol of fresh charge and hot liquid recycle flows through line 16 through reactor 19.

In reactor 19 any sulf-active catalyst can be used. For example, a mixture of cobalt and molybdenum oxides on a carrier or support such as alumina is preferred for mild hydrogenation resulting in hydrodesulfurization of the reaction mixture oil. Employing such sulf-active catalyst, the following reactor conditions have been found to give satisfactory results.

35	Temperature, ° F.....	600—800
	Pressure, p. s. i. g.....	500—3000
	Space velocity, v./v./hr.....	0.1—10
	Hydrogen, s. c. f./b.....	300—5000
40	Recycle, s. c. f./b.....	0—5000

The reactor effluent leaves reactor 19 through line 20 through which it flows to the coking heater. It is preferred to maintain the reactor pressure in the coking heater and settler but the coking operation can also be carried out at pressures below those existing in reactor 19. Accordingly, the following conditions will exist in the coking step:

45	Temperature, ° F.....	800—1200
	Pressure, p. s. i. g.....	0—3000
50	Hydrogen, s. c. f./b.	0—5000

¹ From the hydrogenation reaction and/or fresh hydrogen.

The effluent from reactor 19 flows through coking heater coil 21 in coking heater 22 and thence through line 23 to coke settler 24.

The coke produced by coking the hydrogenated, i. e., at least partially desulfurized reactor effluent is fine and granular. The fine, granular coke settles readily making it possible to remove the coke continuously as a suspension in oil from settler 24 through line 25 under control of valve 26 into coke drop-out depressuring chamber 27 and line 28 under control of valve 29.

Accordingly, the coked reactor effluent flows from coil 21 through line 23 to coke settler 24. In coke settler 24 a separation between the portion of the coking coil effluent vaporous at temperatures of 700 to 1100 and the portion liquid at those temperatures occurs. The vaporous portion, i. e., hydrogen and hydrocarbons boiling below about 650° F. at standard pressure pass from coke settler 24 through line 30, condenser 31 and line 32 to gas-liquid separator 33.

In gas-liquid separator 33 the hydrogen and light hydrocarbons separate from the condensed gasoline and flow from separator 33 through line 34 to the suction side of compressor 35.

Compressor 35 discharges the hydrogen-containing gas into line 36 at slightly above reaction pressure. When necessary or desirable, a portion of the gas in line 36 can be vented to fuel or sulfur recovery through line 37 under control of valve 38.

The gas discharged by compressor 35 is hydrogen-containing recycle gas which flows under reaction pressure from line 36 through line 6 to coil 2 of heater 3 or directly to reactor 19 as described heretofore.

Returning to coke settler 24. The portion of the coking heater effluent which is liquid at the temperature and pressure existing in settler 24 contains the finely divided granular coke. The coke settles readily and is drawn off as a sludge or slurry 39. Thus, with valve 29 closed valve 26 in pipe 25 is opened and the slurry 39 at the bottom of settler 24 flows into coke drop-out pot chamber 27. When pot 27 is filled valve 26 is closed and pot 27 drained by opening valve 29 in pipe 28. The operation is repeated as often as necessary to keep the level of the slurry below gas oil outlet 11 of coke settler 24.

Liquid hydrocarbons substantially free of the fine granular coke produced in the coking unit flow from coke settler 24 through line 11 to condenser 40 and thence through line 41 to cracking units or fractionation units or for other further treatment.

A portion of the hot liquid hydrocarbon withdrawn from coke settler 24 through line 11 can be recycled to the hydrogenation reactor through lines 14 and 15 under control of valve 12 by pump 13 as previously mentioned.

Illustrative of one of the many modifications of the basic concept is the flow-sheet Figure 2.

A heavy petroleum fraction, e. g., having an initial boiling point of at least 450° F. and a 10 percent point of at least 650° F. is pumped at reaction pressure from a source not shown through line 101. Recycle gas containing at least 25 percent hydrogen is pumped by compressor 102 under at least reactor pressure through lines 103 and 104 under control of valve 105 to line 101 where it is mixed with the fresh charge at the rate of 300 to 5000 s. c. f./b. of charge to form a charge mixture. The charge mixture flows through line 101 to coil 106 in heater 107 where the charge mixture is heated to reaction temperature. Alternatively, a portion or all of the recycle gas can be pumped through line 108 under control of valve 109 to line 110 and there mixed with the fresh charge at the rate of 300 to 5000 s. c. f./b.

The heated charge mixture or charge stock flows at reaction temperature from coil 106 through line 110 to line 111 and thence to reactor 112.

Reactor 112 contains a bed of particle-form solid hydrogenation catalyst, preferably sulf-active hydrogenna-

tion catalyst. In reactor 112 the charge stock is subjected to mild hydrogenating conditions such as is provided by the following reaction conditions:

Temperature, ° F. ----- 600 to 800
Pressure, p. s. i. g. ----- 250 to 2000
Space velocity, v./v./hr. ----- 1 to 10
Hydrogen, s. c. f./b. ----- 300 to 5000

The hydrogenated and desulfurized charge together with the hydrogen-containing gas forms a reactor effluent which flows from reactor 112 through line 113. At this point the reactor effluent can either flow through line 113 under control of valve 114 to liquid-gas separator 115 or be diverted through line 116 under control of valve 117 directly to line 118 and coking coil 119 in coking heater 120.

When the reactor effluent flows along line 113 under control of valve 114 to liquid-gas separator 115, the constituents of the reactor effluent boiling below about 450° to 650° F. are vaporous under reactor pressure and separate from the constituents of the reactor effluent liquid at reaction temperature and pressure. The vaporous and gaseous portion of the reactor effluent leaves liquid-gas separator 115 by way of line 121, passes through condenser 122 and flows through line 123 into accumulator 124.

In accumulator 124 the hydrogen and light hydrocarbons separate from the higher boiling, i. e., gasoline boiling range hydrocarbons and flow through line 125 under control of valve 126 to recycle gas line 127 connected to the suction side of recycle gas compressor 102.

The gasoline is withdrawn from accumulator 124 through line 128 to line 129 where it is mixed with gasoline fractions from other sources in the unit.

Returning to liquid-gas separator 115. The portion of the reactor effluent which is liquid at reaction temperature and pressure flows from liquid-gas separator 115 through line 130 to line 118 and thence to coil 119 in coking heater 120.

When the entire reactor effluent is to be treated in the coking unit the flow is as follows: from reactor 112 through lines 113 and 116 under control of valve 117, thence along line 118 to coil 119.

When desirable a portion of the reactor effluent can be sent directly to coil 119 by way of lines 116 and 118 and the balance sent indirectly to coil 119 by way of separator 115 and lines 130 and 118.

In the coking unit the conditions are as follows:

Temperature, ° F. ----- 800-1200
Pressure, p. s. i. g. ----- 0-3000
Hydrogen, s. c. f./b.¹ ----- 30-5000

¹ From reactor 112 preferably.

It will be noted that the hot liquid hydrocarbon 135 in coker settler 134 substantially free from the fine, granular coke produced in the coking unit can be recycled to the coking heater 120 by pump 136. Pump 136 draws hot liquid hydrocarbon from layer 135 in coke settler 134 through line 137 and discharges into line 138. From line 138 the hot liquid hydrocarbon in whole or in part can flow through line 139 under control of valve 140 to line 118 and thence to coil 119 in admixture with reactor effluent flowing through line 118.

The effluent from coking heater 120 flows through line 131 to condenser 132 and thence through line 133 to coke settler 134. The coke produced is fine and granular and suspended in the coking heater effluent. In coke settler 134 that portion of the coking heater effluent vaporous and/or gaseous at the temperature and pressure in the settler separates from the coke laden liquid portion. The vaporous and/or gaseous portion leaves settler 134 through line 141, passes through condenser 142 and line 143 to accumulator 144. In accumulator 144 the hydrogen and light hydrocarbons escape through line 145 to recycle gas line 127. The

components boiling in the gasoline range leave accumulator 144 through line 146 to be mixed with gasoline from other unit sources in line 129.

It will be observed that the liquid components of the coking heater effluent form two layers, a lower layer 147 which is a slurry of fine granular coke in liquid hydrocarbon and an upper layer 135 which is liquid hydrocarbon of about the gas oil range substantially free from coke.

The coke can be withdrawn practically continuously as follows: with valve 148 closed, valve 149 is opened and the coke slurry flows through line 150 into pot or chamber 151 until the pot is filled. Valve 149 is then closed and valve 148 opened and the coke slurry drawn from pot 151 through line 152.

As has been mentioned hereinbefore, the liquid hydrocarbon 135 in settler 134 can be recycled to the coking heater 120. It can also be subjected to a more severe hydrogenation than that to which the charge was subjected in reactor 112.

Thus, liquid hydrocarbon is drawn by pump 136 from layer 135 in settler 134 through line 137. Pump 136 discharges into line 138 with valve 140 in line 139 closed and valve 153 in line 154 open the liquid hydrocarbon flows to line 155. Recycle gas containing hydrogen flows under pressure of compressor 102 through lines 156 and 157 under control of valve 158 to line 155 where it mixes with the liquid hydrocarbon from coker settler 134.

The mixture of liquid hydrocarbon from coker settler 134 and recycle gas flows through line 155 to reactor 159 where the hot liquid hydrocarbon is treated under the following conditions employing any suitable hydrogenation catalyst, e. g., platinum on alumina.

Temperature, ° F. ----- 700 to 1000
Pressure, p. s. i. g. ----- 500 to 3000
Space velocity, v./v./hr. ----- 0.1 to 5
Hydrogen, s. c. f./b. ----- 300 to 5000

It will be noted that reaction conditions in reactor 159 are more severe than in reactor 112.

The effluent from reactor 159 flows through line 160 to liquid-gas separator 161.

In liquid-gas separator 161 those constituents of the effluent of reactor 159 which boil below about 500° F. at normal pressure are in the vapor phase. The vapor phase portion of this effluent leaves separator 161 through line 162. The vapor phase effluent flows through line 162 to condenser 163 and thence through line 164 to accumulator 165 where hydrogen and light hydrocarbons separate from hydrocarbons boiling in the gasoline range. The hydrogen and light hydrocarbons flow from accumulator 165 through line 166 and thence to line 127 to form with hydrogen-containing gases from other portions of the unit recycle gas.

That portion of the contents of accumulator 165 which is liquid at temperature below about 500° F. and normal pressure, i. e., hydrocarbons in the gasoline boiling range flows from accumulator 165 through line 167 to line 129 and thence in admixture with gasoline from accumulators 124 and 144 flows to gasoline treatment, storage and/or distribution. Those skilled in the art will recognize that when desirable or necessary the three streams of gasoline from accumulators 124, 144 and 165 can be held separate or combined in any proportions.

Returning now to liquid-gas separator 161. The liquid portion of the effluent from reactor 159 flows from separator 161 through line 168 to storage or distribution or further treatment. The liquid portion of the effluent from reactor 159 will usually boil in the gas oil range, i. e., 500°-650° F., and will be a highly saturated material of relatively low aromatic hydrocarbon content.

Alternatively a portion of the liquid portion of the effluent from reactor 159 flows from line 168 through line 169 under control of valve 170 to the suction side of pump 136 and thence to reactor 159 for further treat-

ment therein in conjunction with the liquid hydrocarbon from layer 135 in settler 134. In other words a portion of the liquid effluent from reactor 159 is recycled thereto.

I claim:

- 5 1. A method of producing fine granular particles of petroleum coke which comprises mildly hydrogenating in a first zone a mineral oil fraction boiling above about 600° F. and substantially devoid of solid matter extraneous thereto in the presence of sulf-active hydrogenation catalyst at a temperature within the range of about 600° to about 800° F. at a pressure within the range of about 250 to about 3000 p. s. i. g. at a space velocity within the range of about 0.1 to about 10 v./v./hr. in the presence of about 300 to about 5000 s. c. f. of hydrogen per barrel of said mineral oil fraction to obtain a first zone effluent substantially devoid of solid matter extraneous to said fraction comprising hydrogen and hydrocarbons boiling above about 600° F., passing said first zone effluent substantially devoid of solid matter extraneous to said fraction through a coking zone at a temperature within the range of about 800° to about 1200° F. at a pressure up to about 3000 p. s. i. g. in the presence of up to about 5000 s. c. f. of hydrogen per barrel to obtain an at least partially liquid coking zone effluent substantially devoid of solid matter extraneous to said mineral oil fraction comprising hydrogen, hydrocarbons boiling in the gasoline range and fine granular particles of coke suspended in liquid hydrocarbons boiling above the gasoline range including gas oil hydrocarbons, separating said hydrogen and hydrocarbons boiling in the gasoline range from a liquid fraction comprising fine granular particles of coke suspended in hydrocarbons boiling above the gasoline range and including hydrocarbons boiling in the gas oil range, stratifying said liquid fraction to obtain an upper liquid layer comprising hydrocarbons boiling in the gas oil range substantially devoid of said fine granular particles of coke and a lower liquid layer comprising hydrocarbons boiling above the gasoline range and said fine granular particles of coke suspended therein, and separately withdrawing said upper liquid layer comprising hydrocarbons boiling in the gas oil range substantially devoid of said fine granular particles of coke and said lower liquid layer comprising hydrocarbons boiling above the gasoline range and said fine granular particles of coke suspended therein.
- 10 2. The method set forth and described in claim 1 wherein the coking zone effluent is separated under a pressure substantially the same as that in the coking zone.
- 15 3. The method as set forth and described in claim 1 wherein at least part of the first zone effluent is separated into a gaseous fraction comprising hydrogen and hydrocarbons boiling below the gas oil range and a liquid fraction comprising hydrocarbons boiling above the gasoline range, and wherein the aforesaid liquid fraction of said separated first zone effluent is passed through said coking zone.
- 20 4. The method as set forth and described in claim 1 wherein at least part of the withdrawn upper liquid layer of the coking zone effluent substantially devoid of fine granular particles of coke is recycled to the coking zone.
- 25 5. The method as set forth and described in claim 1 wherein at least part of the withdrawn upper liquid layer of the coking zone effluent substantially devoid of fine granular particles of coke is subjected in a second hydrogenation zone to hydrogenation conditions more severe than exist in said first zone and at a temperature within the range of about 700° to about 1000° F. at a pressure within the range of about 500 to about 3000 p. s. i. g. at a space velocity within the range of about 0.1 to about 5 v./v./hr. in the presence of about 300 to about 5000 s. c. f. of hydrogen per barrel.
- 30 6. The method as set forth in claim 1 wherein at least
- 35
- 40
- 45
- 50
- 55
- 60
- 65
- 70
- 75

part of the withdrawn upper liquid layer of the coking zone effluent substantially devoid of fine granular particles of coke is subjected in a second hydrogenation zone to hydrogenation conditions more severe than those in said first zone and at a temperature within the range of about 700° to about 1000° F. at a pressure within the range of about 500 to about 3000 p. s. i. g. at a space velocity within the range of about 0.1 to about 5 v./v./hr. in the presence of about 300 to about 5000 s. c. f. of hydrogen per barrel and in the presence of a catalyst comprising platinum on alumina.

7. The method as set forth and described in claim 1 wherein the sulf-active hydrogenating catalyst comprises a mixture of cobalt and molybdenum oxides.

8. The method as set forth and described in claim 1 wherein the catalyst in the first zone comprises a mixture of oxides of cobalt and molybdenum, and wherein at least a part of the withdrawn upper liquid layer of the coking zone effluent substantially devoid of fine granular particles of coke is subjected in a second hydrogenation zone to hydrogenation conditions more severe than those in said first zone at a temperature within the range of about 700° to about 1000° F. at a pressure within the range of about 500 to about 3000 p. s. i. g. at a space velocity within the range of about 0.1 to about 5 v./v./hr. in the presence of about 300 to about 5000 s. c. f. of hydrogen per barrel and in the presence of a catalyst comprising a mixture of oxides of cobalt and molybdenum.

9. The method as set forth and described in claim 1 wherein the catalyst in the first zone comprises a sulf-active hydrogenating catalyst, and wherein at least a part of the withdrawn upper liquid layer of the coking zone effluent substantially devoid of fine granular particles of coke is subjected in a second hydrogenation zone to hydrogenation conditions more severe than those in said first zone at a temperature within the range of about 700° to about 1000° F. at a pressure within the range of about 500 to about 3000 p. s. i. g. at a space velocity within the range of about 0.1 to about 5 v./v./hr. in the presence of about 300 to about 5000 s. c. f. per barrel and in the presence of particle form solid hydrogenating catalyst.
